UNITED STATES PATENT OFFICE.

CHARLES F. VOLLMER, OF DENVER, COLORADO.

CONVERTIBLE CHAIR AND TABLE.

1,220,300.

Specification of Letters Patent. Patented Mar. 27, 1917.

Application filed May 11, 1915. Serial No. 27,397.

To all whom it may concern:

Be it known that I, CHARLES F. VOLLMER, a citizen of the United States, residing at Denver, in the county of Denver and State 5 of Colorado, have invented certain new and useful Improvements in Convertible Chairs and Tables, of which the following is a specification.

This invention relates to convertible chairs 10 and tables, to permit use of the device either as a chair, or table, at the option of the user.

An object of the invention is to equip a Morris chair with suitable means to permit 15 its being converted into a table when desired, without making any material alterations in the chair, the table being swung into an operative or inoperative position, at the option of the user, without the use of any 20 parts other than the inherent chair structure.

Another object is to associate an improved 25 book holder, with one of the arms of the chair, to permit the holder being placed directly in front of the occupant of the chair for convenience in reading.

A further object of the invention is to provide a leg rest, for yieldingly supporting the legs, and flexible under movement of the latter, to prevent cramping the legs, frequently caused by the immovability of a 30 fixed support.

Other objects as well as the nature, characteristic features and scope of my invention will be more readily understood from 35 the following description taken in connection with the accompanying drawings and pointed out in the claims forming a part of this specification.

Referring to the drawings:

40 Figure 1 is a longitudinal sectional view of a chair constructed in accordance with my invention, dotted lines being used to indicate the position of the back when the chair is used as a table,

45 Fig. 2 is a front elevational view of the improved chair, the cushion of the back being removed to disclose details,

50 Fig. 3 is a rear elevational view of the chair, showing to advantage the hinged leaves of the table and the manner in which they are held together when not in use,

Fig. 4 is a top plan view of the back of the chair, when the same is used in the ca-

pacity of a table, the hinged leaves being shown in open position thereon, 55

Fig. 5 is a plan view of one of the arms of the chair,

Fig. 6 is a detail enlarged fragmentary view of the chair body showing the book support in an operative position thereon, 60

Fig. 7 is a plan view of the chair back pivoting frame.

In the drawings a chair body is provided comprising the usual legs 1 with which the seat-supporting portion 2 is associated, the 65 latter having a bar 3 depending from its lower face and at the front of said seat-supporting portion, the outer face of which has a longitudinally extending groove formed therein. A seat 4 of the usual or 70 any desired configuration is mounted upon the seat-portion 2 in the usual manner. Arms 5 are associated with the upper terminals of the legs 1, each of which has a portion of one of its lateral margins removed, 75 as indicated at 6 and shown to advantage in Fig. 5, while its end is reduced and provided in its upper face with transverse grooves 7. A back 8 is movably mounted between the arms 5 of the chair and is in 80 pivotal connection with the seat-supporting member 2, through the medium of a U-shaped yoke member 9, the latter being of a substantially U-shaped configuration and having its bight passed through loop-straps 85 10 on the seat-supporting portion 2, as shown to advantage in Fig. 1. The free terminals of the arms of the U are turned at right angles, as at 11, as shown to advantage in Fig. 7, for pivotal engagement with loop-straps 12 on the inner face of the back 8. It

will be noted that the back 8 is preferably of an oblong configuration, as illustrated in Fig. 2, and extends appreciably below the lower face of the seat-supporting portion 2 90 95 and above the upper faces of the arms 5.

Leaves 13 are hingedly engaged with the rear face of the back 8, each of said leaves having its outer marginal edges coincident with the marginal edges of the back 8, while 100 the proximate lateral margins of said leaves 13 are spaced from each other, as shown in Fig. 3, and are held from displacement by retaining means 14. It will be observed that the inner face of the back 8 is provided with 105 an upholstered portion 15 so as to provide

a more comfortable rest. When the chair is used in the capacity of a table, the upholstered portion 15 provides a support for the back 8, as indicated by the dotted lines 5 in Fig. 1, since the upholstered portion is engaged with the upper faces of the arms 5. The arms of the U-shaped yoke 9 engage with shoulders 16 which are provided by cutting away portions of the arms 5, as indicated at 6, referred to above, thereby preventing displacement of the back. The leaves 13 are permitted to be operated outwardly, when desired, so as to provide a relatively large table. When the device is 10 desired to be used again as a chair, pressure is merely exerted on the back 8, so as to throw the same rearwardly, disengaging the arms of the U-shaped yoke 9 from the shoulders 16. The back will assume its normal 15 position when shoved sufficiently rearwardly and may be held in any desired recumbent or straight position by a rod 17 which extends transversely of the chair and is engaged in the recesses 7 on the upper faces of the arms 20 5 of the chair.

A foot rest 18 is associated with the bar 3 and comprises a base portion 19, one of the lateral margins of which is engaged in the longitudinal groove in the front face of the 30 bar 3, while the opposite lateral margin is in hinged engagement with one of the lateral edges of a movable body member 20, the latter being normally held in an inclined position by a rod 21, one end of which 35 is engaged with the inner face of the body member 20, while the opposite end extends through an opening 22 in the base 19 of the foot supporting member, and has an enlarged head 23 formed on its free terminal. Coil-springs 24 and 24' are engaged 40 with the rod 21, the former being interposed between the body member 20 and the base 19, while the latter spring is interposed between said base 19 and the head 23, thereby 45 yieldingly supporting the body portion 20 in the desired position. It will therefore be seen that the foot-supporting portion is arranged in close proximity to the seat 4 of the chair, so as to support the legs of the 50 occupant of the chair, thereby preventing the legs from being cramped which as is well known, is usually caused by being engaged with a perfectly rigidly supporting medium. Moreover, by inclining the body member 20, it is seen that a more normal 55 recline of the legs is permitted, which is especially desirable when the occupant of the chair is in a recumbent position. The support is, of course detachable from the bar 3, so as to preclude possibility of its interference, when the device is used as a table.

A book-supporting member is associated

with one of the arms 5 of the chair and comprises a supporting beam 25, one end of which is hinged to one of the chair arms, 65 permitting the beam to be swung into engagement with the upper face of the chair arms 5, transversely of the chair, so as to dispose said beam directly in front of the occupant of the seat 4. A book engaging 70 member 26 is hingedly engaged with the beam 25 and is provided with a right-angled abutment 27 on its lower end, to prevent casual displacement of the book. A supporting staff 28 is hinged on the rear face 75 of the supporting member 26 to retain the latter in an inclined position. From this construction, it will be observed that the beam 25 may be swung to one side of the chair when not in use, as shown in Fig. 2, 80 furthermore that the book-engaging member 26 may be folded into snug engagement with the beam 25, so as to occupy a minimum amount of space when not in use, thereby 85 providing a compact structure.

It will be understood that the above description and accompanying drawings comprehend only the general and preferred embodiment of my invention and that various minor changes in details of construction, 90 proportion and arrangement of parts may be made within the scope of the appended claims without sacrificing any of the advantages of my invention.

Having thus fully described my invention, 95 what I claim as new and desire to secure by Letters Patent is:

1. A convertible chair and table including a body having side arms, the back of said chair being operable into a position superposed above the side arms to provide a table, and a relatively thick member carried by one side of the chair back to provide a cushioned back, said member adapted to engage the chair arms for holding the back spaced from the latter when used as a table, and to prevent mutilation of the side arms.

2. A convertible chair and table including a body equipped with side arms, a back movably carried by said body and movable into a position to be supported by said arms to provide a table, and a wire strand in pivotal engagement with said body and back and engageable with said side arms to limit the forward movement of the back, said strand comprising an axis to facilitate movement of the back.

In testimony whereof I affix my signature in presence of two witnesses.

CHARLES F. VOLLMER.
